UNITED STATES PATENT OFFICE.

WALTER KELLNER, OF BARMEN-WECHLINGHAUSEN, GERMANY, ASSIGNOR TO CARL F. AHLSTROM AND OTTO J. AHLSTROM, OF NEW YORK, N. Y.

BRAIDING-MACHINE.

1,206,228.

Specification of Letters Patent. Patented Nov. 28, 1916.

Original application filed August 9, 1912, Serial No. 714,190. Divided and this application filed August 26, 1914. Serial No. 858,643.

To all whom it may concern:

Be it known that I, WALTER KELLNER, a subject of the Emperor of Germany, residing at Barmen-Wechlinghausen, Wiescherstrasse, Rhenish Prussia, Germany, have invented new and useful Improvements in Braiding-Machines, of which the following is a specification.

This invention relates to braiding machines and the application on which this patent is granted was a division of my co-pending application for improvements in braiding machines, Serial No. 714,190 now Patent No. 1,193,554, Aug. 8, 1916. The invention relates particularly to novel means for temporarily locking a carrier at the stations or stopping places where their braiding movement is arrested.

A principal object of the invention is to provide improved means for enabling the carriers to be held temporarily out of the path of travel and for projecting them, when desired, back again into the path of travel so that their braiding movement will proceed. The arrest of the movements of the carriers at the stations, and their release is controlled by a pattern mechanism.

A general object of the invention is to provide a very simple mechanism for the purpose set forth.

Further objects of the invention will appear more clearly hereinafter.

In the drawing which fully illustrates the preferred embodiment of my invention: Figure 1 is a vertical section taken at one of the stations and illustrating one of my devices, contiguous parts of the mechanism being shown associated with my device. Fig. 2 is a plan view showing the arrangement of the track or path that the carriers take, and indicating its relation to one of my devices. Fig. 3 is a side elevation and partial section of my device. Fig. 4 is an end elevation of my device looking from the rear, that is from the side remote from the path of the carrier, Fig. 5 is a plan of the upper portion of the device showing certain contiguous parts, other parts of the mechanism being omitted.

Referring more particularly to the parts, 1 indicates the top plate of the braiding machine in which the intersecting guide tracks 4 are formed. A short distance below the top plate is the under plate 2, pillars 3 con-

necting the two plates serving as the axes 55 about which the drivers for moving the spindles 5 of the carriers and their gearing revolve. The drivers and the gearing being well known, are omitted from the drawing. At the intersections of the guide tracks 4 60 are stations 6 where the carriers disengage from the drivers, pause, and are arrested in their travel. These stations are formed by cutting away the plate 1 at each intersection of the tracks 4 and on opposite sides thereof. Opposite each station is a switch 4^a of the usual type for directing the movement of the carriers.

In applying my invention, I prefer to provide between the plates 1 and 2 a bracket 70 7, and mounted on this bracket I provide means for engaging the carrier to hold it, and later to release it and return it into its path of travel, when desired. For this purpose, I prefer to provide a rocking lever 8 75 preferably provided with an upwardly extending arm 9 which is preferably of round form, and on this arm there is adjustably mounted a locking member 10 preferably in the form of an elongated plate the forward 80 end of which projects out to a point near the path of travel of the carrier, said plate 10 being mounted rigidly on a collar 10^a which is adjustable on the arm by suitable means such as set screw 10^b.

In the upper end of the bracket 7 I provide another movable member 11 which is preferably in the form of a slide which is guided to slide horizontally toward and away from the path of the carrier; this slide 90 constitutes an ejector one of the functions of which is to return the carrier to its normal path of travel when it is released, I prefer to construct this ejector however, so that it co-operates with the locking member to hold 95 the carrier in the position indicated in Figs. 1 and 2, for this purpose, the projecting end of the ejector is preferably provided with inclined guide faces 12 and a centrally disposed edge preferably having rudimentary 100 notch or seat 13. Co-operating with this seat 13 I prefer to form a slight notch or seat 14 by providing a raised portion 15 on the upper face of the locking member 10, and this raised portion 15 is preferably formed with inclined guide faces 16. The guiding faces 12 and 16 are arranged so that when the carrier comes between them they will

guide it into position between the seats 13 and 14 which will then hold the carrier until it is released.

I prefer to provide resilient means which 5 will hold the ejector and locking member in their retracted position with these two parts substantially in parallelism and in position to hold the carrier out of reach of the travels of the machine. This is preferably accom- 10 plished by means of a spring 17 the upper end of which is attached to the tail or rear end of the locking member 10, the lower end being attached as at 18, to the lower portion of the bracket 7.

15 In order to actuate the ejector or slide 11, I prefer to provide the slide with an opening 19 into which the upper end of the arm 9 extends, said arm passing through an elongated slot 20 in the head of the bracket, 20 which permits a forward and return movement of the arm 9 when the device is being actuated.

The angle lever 8 preferably includes the usual substantially horizontal arm 21 which 25 may be actuated by the pattern at any suitable time, by means of a link 22.

The operation of this device is substantially the same as the device set forth in the application Serial Number 714,190. Features 30 of the mode of operation will now be described.

As a carrier approaches a station, it is directed out of its regular path of travel in the braiding movement and comes into contact 35 with one of the guiding faces 16 and the corresponding guiding face 12, and these faces guide the carrier into position between the seats or rudimentary notches 13 and 14, at which point the movement of the carrier 40 is arrested. As illustrated most clearly in Figs. 3 and 5, there is a slight amount of lost motion or play of the arm 9 in the slot 19. This permits a slight independent movement of the locking member 10 which 45 is sufficient to enable the carrier to come into the position in which it is illustrated in Fig. 1. At the proper moment, which is determined by the particular pattern of the braid, the link 22 is pulled down so as to 50 rock the vertical arm 9 forward; this depresses the locking member 10 which engages the outer side of the carrier and releases the carrier, and at the same time the arm 9 causes an outward movement of the 55 slide or ejector 11 which pushes the carrier

outwardly and returns it to its regular path of movement in the braiding mechanism.

It is understood that the embodiment of the invention described above is only one of the many forms or embodiments that the invention may take, and I do not wish to be limited in the practice of the invention, nor in my claims to the particular embodiment set forth.

What I claim is:—

1. In a braiding machine, the combination 65 with a carrier movable along a track and guided to move to a station out of the path of travel, an upwardly extending rocker arm at the station, an adjustable locking member 70 on said arm, said locking member having opposed inclined guiding faces, an ejector at the upper end of said arm and adapted for rectilinear movement upon the movements of said arm, said ejector having inclined guiding faces opposed to the guiding faces on said locking member, the guiding faces of the locking member and ejector being designed to engage and hold the carrier, and means 75 yieldingly holding the locking member and ejector in retracted position with the carrier out of reach of the drivers of said machine.

2. In a braiding machine in combination, 80 a carrier movable along a track and adapted to stop at determined stations therein out of the path of travel, an upwardly extending rocker arm, an adjustable locking member 85 having means for engaging one side of the carrier on said arm, an ejector adapted 90 to engage the side thereof opposite to the side engaged by the locking member, the said ejector being engaged by the upper end of said rocker arm, means yieldingly holding the locking member and ejector in re- 95 tracted position with the carrier out of reach of the drivers of said machine, and means for actuating said rocking arm to cause the substantial simultaneous canting of the locking member for the release of the carrier 100 and to cause rectilinear movement of the ejector to return the carrier to the path of travel.

In testimony whereof I have hereunto set my hand in presence of two subscribing 105 witnesses.

WALTER KELLNER. [L.S.]
